UNITED STATES PATENT OFFICE.

JOSEF TISSLER, OF PHILADELPHIA, PENNSYLVANIA.

DESIGN FOR AN ELECTRIC FLOOR LAMP.

Application filed August 9, 1928. Serial No. 27,753. Term of patent 3½ years.

To all whom it may concern:

Be it known that I, JOSEF TISSLER, a citizen of the United States of America, and a resident of Philadelphia, in the county of Philadelphia and State of Pennsylvania, have invented a new, original, and ornamental Design for an Electric Floor Lamp, of which the following is a specification, reference being

had to the accompanying drawing, forming part thereof.

The figure is a perspective view of an electric floor lamp, showing my new design.

I claim:

The ornamental design for an electric floor lamp, as shown.

JOSEF TISSLER.
